SYNCHRONIZING SYSTEM

Application filed December 23, 1931. Serial No. 532,726.

My invention relates to telegraph systems, and more particularly to a type of corrector system for use with synchronous telegraphy.

Telegraph systems of this type usually comprise two or more commutators or distributors with means for maintaining the brushes of said distributors in synchronism with each other.

As is well known in the art, when the brushes at the receiving end of a synchronous telegraph system are out of phase with those at the transmitting end, it is necessary to provide means for stepping the brushes back into phase at frequent intervals.

15 The object of my invention is to provide a simple correcting system which will function to step the brushes back at frequent intervals by utilizing the signalling impulses, thereby eliminating the loss of transmission time.

20 In order to accomplish the correcting results I employ a differentially wound locking relay which is controlled in part by the line relay responsive to the transmitted impulses, and in part by the co-operation of 25 certain mechanical parts associated with the distributor.

Various features of my invention will be pointed out in the description to follow.

The single figure in the drawing shows the 20 preferred embodiment of my invention.

Referring to the drawing:

A drive shaft 45 for the distributor, driven by means not shown, carries a fly wheel 50 and a freely rotating brush carrier 47. The 25 brush carrier has a gear wheel 48 formed integral therewith, which meshes with a pinion 39 secured to a short shaft 40 which is journalled in a control disc 41 operatively secured to shaft 45 by any suitable means such as pin 42.

40 The other end of the shaft 40 has a star wheel 46 secured thereto which is prevented from rotating by a spring actuated detent roller 49 carried by control disc 41. The magnet 15 is provided with an armature 17 which, when 45 operated, brings the pin 18 into the path of star wheel 46.

The arm 13 is controlled by a projection 44 on the disc 41 for controlling the circuit of magnet 15.

50 A polarized line relay is shown at 1, the

tongue of which is connected to the winding of polarized relay 2. The tongue of relay 2 follows the received line signals. When the tongue of relay 2 is resting against its spacing contact S, the condenser 3 will be discharged through resistance 4. When a marking signal is received, the tongue of relay 2 will move over to the marking contact M and the condenser 3 will be charged from battery 5. The charging current for condenser 3 will always flow through the windings of locking relay 6. If the brush 7 is in proper phase relation with the received signals, then brush 7 will be on the B segments at the instant the tongue of relay 2 arrives at its marking contact, and the charging circuit of condenser 3 will be as follows: from battery 5, through condenser 3, marking contact M, windings 8 and 9 of relay 6, segment B, brush 7, and thence through solid ring 10 to ground. It should be noted that the charging impulse goes through windings 8 and 9 in series and that these windings are connected in opposition. Since windings 8 and 9 have an equal number of turns, it will be apparent that the armature 11 of relay 6 will not be operated. The resistance of windings 8 and 9, however, limits the charging current of condenser 3 and thereby prevents damage to the contacts of relay 2 or the distributor segments and brushes. When the brush 7 is out of phase with the received signal, the brush will be on the A segment at the instant that the tongue of relay 2 arrives at its marking contact.

The path of the charging impulse of condenser 3 will be as follows: from battery 5, through condenser 3, contact M, winding 8 of relay 6, segment A, brush 7, solid ring 10, and thence to ground. Since the charging current, in this case, passes through only one winding of locking relay 6, the armature 11 will be attracted and the relay will lock up through the following circuit: ground, battery 12, contacts 13 and 14, winding of corrector magnet 15, tongue 11, winding 16, and thence to ground. The energization of magnet 15 will attract armature 17 which will cause the pin 18 to be placed in the path of star wheel 46. At a certain point in the revolution of the distributor the pin 18 will

engage the star wheel 46 and cause the brushes to be stepped back a small amount, which will tend to put the brushes into the proper phase relation with the received signals. Immediately after the pin 18 has engaged with star wheel 46, contacts 13 and 14 will separate momentarily, thereby unlocking relay 6 and de-energizing corrector magnet 15. It should be mentioned at this time that the cam which operates the unlocking contacts is not shown in the proper position with relation to star wheel 46, but is merely shown in this position for convenience. It should be kept in mind that the brushes of the distributor are normally running a trifle fast and it is necessary that the brushes be stepped back at occasional intervals.

What is claimed is:

1. In a telegraph system, the combination of a line relay for receiving impulses of different characteristics, a condenser, a distributor normally rotating, a circuit arrangement whereby said condenser is charged by a change of impulses received by said line relay, a corrector relay provided with two windings, and circuit arrangements whereby said condenser charges through both of said windings when said distributor is rotating normally and charges through but one of said windings when said distributor is rotating abnormally.
2. In a telegraph system, the combination of a rotating distributor, a corrector relay provided with two windings, a source of charging current, means for causing said charging current to flow through both windings of said corrector relay when said distributor is normally rotating and for causing charging current to flow through but one of said windings when said distributor is rotating abnormally.
3. In a telegraph system, the combination of a rotating distributor, a differentially wound corrector relay, a condenser and a source of charging current therefore associated with said relay, means for causing charging current to flow through the windings of said relay in series opposition when said distributor is correctly phased, means for causing charging current to flow through only one of said windings when said distributor is incorrectly phased, and mechanical means under control of said differential relay to correct said distributor phasing when a single winding only of said differential relay is energized.

4. In a synchronizing system for telegraph apparatus, a distributor comprising a rotating contactor and fixed corrector contacts operatively associated therewith, a driving member for said contactor, mechanical means for angularly displacing said rotating contactor in respect to said driving means, a differential relay having its windings connected in series opposition when said ro-

tating contactor connects certain of said fixed corrector contacts and having a single winding in circuit when said contactor connects other of said contacts, and means for operating said mechanical means when said differential relay is operated, said operation resulting from a current flow through one winding only of said relay.

5. In a synchronizing system, a distributor comprising rotatable brushes, solid and segmented contact rings associated therewith, and a driving means for said brushes, and means for adjusting the position of said brushes in respect to said driving means, said last-mentioned means comprising a differentially wound relay controlled by the position of said brushes on said contact rings, said relay having a current flow therethrough at all times at which adjustment of said brushes is possible, said current flow being ineffective to operate said relay when adjustment is unnecessary.

6. A synchronizing system for telegraph apparatus, comprising a signal receiving relay, a polarized relay connected thereto and operated thereby, a distributor comprising solid and segmented contact rings, rotating brushes and driving means therefor, a differentially wound relay having its differential windings connected in series with multiplied odd segments of said segmented rings and a single one of said differential windings connected to multiplied even segments of said segmented rings, mechanical means adapted to adjust the angular position of said brush with respect to said driving means at a fixed point in the cycle of the latter, a circuit connecting said differentially wound relay and said mechanical means, a condenser in circuit with said differential relay windings, the charging current of said condenser serving to operate said differential wound relay and said mechanical means when said brushes connect said solid ring and one of said even segments, said charging current flowing through both said windings in series opposition when said brushes connect said solid ring and one of said odd segments, said differential relay and associated mechanical means being unoperated thereby.

7. In a system for maintaining synchronism between two electrically remotely located rotating bodies, driving means for said bodies one of said driving means normally rotating more rapidly than the other, a line, means for transmitting signals over said line at a speed regulated by said slower rotating body, a receiving relay operated by said signals, a polarized relay operated by said receiving relay, a differential relay operated by current flow through a single winding thereof when said rotating bodies are electrically angularly displaced with respect to each other and said polarized relay armature is lying on one of its contacts, said dif-

ferential relay being unoperated by a current flowing through both its windings when said rotating bodies are in phase, and mechanical means controlled by said differential relay for altering the angular displacement of said faster rotating body in respect to its driving means to phase the slower and faster rotating bodies.

8. A synchronizing system for telegraph apparatus, comprising a polarized relay operable in accordance with received signals, a distributor comprising corrector contacts and a contact brush, driving means for said brush, means for angularly displacing said brush with respect to said driving means, a differentially wound relay in circuit with said polarized relay and said corrector contacts, said differential wound relay having its windings connected in series opposition when correction is not needed and having a single winding in circuit when correction is needed, and a corrector magnet controlled by said differentially wound relay and operated only when said differentially wound relay has current flowing through but a single winding.

25 In witness whereof, I hereunto subscribe my name this 22nd day of December 1931.
